UNITED STATES PATENT OFFICE

145,748

DESIGN FOR A FABRIC

Arthur Y. Park, Los Angeles, Calif.

Application February 19, 1946, Serial No. 126,707

Term of patent 3½ years

(Cl. D92—1)

To all whom it may concern:

Be it known that I, Arthur Y. Park, a citizen of the United States of America, residing at the city of Los Angeles, in the county of Los Angeles and State of California, have invented a new, original, and ornamental Design for a Fabric, of which the following is a specification, reference being had to the accompanying drawing, forming a part thereof.

The figure in the drawing is a plan view of a fabric showing my new design.

A complete design unit is disclosed, which unit repeats vertically over the fabric. The full width of the fabric is disclosed horizontally on the drawing.

I claim:

The ornamental design for a fabric, as shown and described.

ARTHUR Y. PARK.
